(57) **CLAIM**

The ornamental design for a compact rotorcraft seating assembly as shown and described.

DESCRIPTION

FIG. 1 is a forward view of a compact rotorcraft seating assembly showing the claimed design thereof;

FIG. 2 is an aft view of the compact rotorcraft seating assembly of FIG. 1;

FIG. 3 is a right-side profile view of the compact rotorcraft seating assembly of FIG. 1;

FIG. 4 is a left-side profile view of the compact rotorcraft seating assembly of FIG. 1;

FIG. 5 is an overhead view of the compact rotorcraft seating assembly of FIG. 1;

FIG. 6 is an underside view of the compact rotorcraft seating assembly of FIG. 1;

FIG. 7 is a right-side aft isometric view of the compact rotorcraft seating assembly of FIG. 1;

FIG. 8 is a left-side aft isometric view of the compact rotorcraft seating assembly of FIG. 1;

FIG. 9 is a left-side forward isometric view of the compact rotorcraft seating assembly of FIG. 1; and,

FIG. 10 is a right-side forward isometric view of the compact rotorcraft seating assembly of FIG. 1.

The broken lines in the figures illustrate portions of the compact rotorcraft seating assembly that form no part of the claimed design.

1 Claim, 10 Drawing Sheets
